UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

CORRUGATED HOPPER DOOR FOR RAILWAY CARS.

Application filed August 14, 1925. Serial No. 50,223.

The invention relates to a railway dump car having a "door" forming a part of the car for retaining the load therein which door is provided with hinges adjacent one 5 of its edges and is capable of being "dropped" or swung open so that the load in discharging slides or passes over the upper surface of the door. Any means of raising the door to the closed position and any 10 means for locking and releasing the door may be employed with my device.

Experience has shown that a slight projection on the upper surface of such a door causes the discharging load to bank up and 15 seriously retard the unloading of the car sometimes completely obstructing the opening and at other times causing some of the material to remain in the car. It is essential that the entire load be discharged when the 20 doors are dropped in order to conserve time when the cars are being used to ballast a main line track, or to eliminate the necessity of maintaining men to remove any small portion of the load that remains in 25 the car after the doors are dropped.

The relative position of the rail, the truck (and other parts of the car) and service 30 conditions also regulate the inclination of the door after it is dropped, so that it is seldom possible to allow the doors to drop to a vertical position; in fact, in a drop bottom gondola car the doors are positioned only about 30 degrees from a horizontal 35 plane when in open position.

A door for this purpose must be very 40 strong and durable because:

First, it is a part of the floor of the car and as such must sustain the load as well as the impact blow of the load when the car is 45 in motion. Second, the car is frequently loaded from chutes or tipplers from a height of ten feet or more, causing the load to be dropped directly upon the doors. Third, clam shell buckets are frequently used to 50 unload such cars and it is not uncommon for these buckets to rest upon and drag over the doors. Fourth, when the door suddenly comes to rest after being dropped it is not only subjected to a severe shock but it must 55 sustain the severe impact thrust of the load which, of course, follows the door. Fifth, as the load is theoretically equally distributed, the door must be strong over its entire area and must be capable of transmitting the resulting stresses to the car body.

without much deflection and no substantial distortion. Any bending of the door or drooping of the corners would cause a leak of the lading, especially of such fine material as sand, cherts, etc. Any bending or warping might interfere with the complete closing and locking of the door. 60

As it costs as much to haul a ton of car as it does to haul a ton of paying freight, it is imperative that the car and any part 65 thereof be as light as possible. Furthermore, the total weight of the car and freight is determined by the strength of certain standard axles, so that the lighter the car the greater amount of freight a given car 70 will be allowed to carry.

Various means have been used to strengthen a plate metal door to meet the service conditions. Reinforcements have been secured to the door thus materially 75 increasing its weight which is objectionable. Various integral reinforcements (such as corrugations) have been formed in metallic plates which, however, interfere with the discharge of the loading or have other 80 objectionable features. 85

One of the objects of the invention is to obtain a strong durable door for a load discharging freight car made of a metallic plate formed with integral corrugations 85 which are positioned approximately normal to the direction of discharge of the lading but are of such configurations as not to interfere with the movement of the cargo when leaving the car. 90

Another object of the invention is to provide an arrangement whereby the corrugations are positioned substantially normal to the supporting hinges and yet will not interfere with the discharge of the lading. 95

The advantages of my door are applicable to any door of a freight car over which the lading moves when being discharged from the car, such as drop bottom general service cars (used in the drawings) hopper cars, 100 swinging side doors or hopper bottom coal cars, etc.

In the drawings:

Fig. 1 shows a portion of a railway car with my invention applied thereto. 105

Fig. 2 is a section on line 2—2 of Fig. 1 showing the door in open position.

Fig. 3 is a section on line 3—3 of Fig. 1.

Fig. 4 is an enlarged section through a corrugated portion of the door. 110

To illustrate one adaptation of my device, I have shown a so-called "general service" drop bottom gondola car wherein the major portion of the floor consists of drop doors. The door openings are surrounded by the center construction, side wall and cross diaphragms. In normal or closed position the door completely closes this opening and, in fact, is a trifle larger on all sides than the opening so as to provide a lap joint between the door and the car frame members. The hinge beams are hinged to the center construction and are supported adjacent the side wall by the raising or locking mechanisms. Any convenient stop, such as 2, may be used to limit the downward movement of the door.

The door is made of a metallic plate (preferably steel which is reinforced with integral corrugations 3 resting upon hinge beams 4, the corrugations extending continuously their full depth between the hinges and then decreasing in depth (5) and merging into the original plane of the plate 6 and preferably in close proximity to the stiffening flanges 7, which are formed at the opposite edges of the door. This arrangement provides a very efficient double supported beam with overhanging end portions and obtains a cooperation between the hinge beams, the corrugations and the flanges.

The corrugations are each formed on a radius larger than the depth of the corrugation so that it presents substantially no

resistance to the easy movement of the load over the doors when discharging. The corrugations may project in one direction from the original plane of the sheet or may project oppositely if desired. If there are flat portions between the corrugations they are preferably the same width as the corrugations.

I claim:

1. A door for a railway car made of a metallic plate reinforced with integral corrugations formed on an arc of a circle having a radius larger than the depth of the corrugation, and flat portions in the original plane of the plate positioned between said corrugations of the same width as the corrugations.

2. A door for a railway car made of a metallic plate reinforced with integral corrugations projecting alternately upwardly and downwardly, each corrugation formed on an arc of a circle having a radius larger than the depth of the corrugation, and flat portions in the original plane of the plate positioned between said corrugations.

3. A door for a railway car made of a metallic plate reinforced with integral corrugations projecting alternately upwardly and downwardly, each corrugation formed on an arc of a circle having a radius larger than the depth of the corrugation, and flat portions in the original plane of the plate positioned between said corrugations of the same width as the corrugations.

GARTH G. GILPIN.
